THREAD CUTTER DEVICE WITH FINGER SUPPORT

Josephine Di-Bella Herz, Verona, N. J.

Application March 13, 1950, Serial No. 149,383

2 Claims. (Cl. 30—291)

1

This invention relates generally to thimbles and in particular to a thimble having a thread-cutting device thereon.

Thimbles are well known in the art of sewing and are provided for the purpose of protecting the fingers against punctures by the needle. Thimbles are generally of a limited size sufficient to be worn on the end of a finger and still permit flexibility of the fingers.

A person sewing by hand must necessarily cut the thread many times during the sewing of each article and this is conventionally accomplished by means of scissors or the like. Therefore, the sewer must stop and pick up the scissors each time a thread is to be cut, an operation which is time-consuming and irritating since scissors are readily hidden by the material.

It is proposed by the present invention to have cutting means instantly and constantly available to the sewer and thus permit rapid accomplishment of the sewing task.

Therefore, the principal object of the invention resides in the provision of a thimble or other tubular member of such size as to be carried snugly on the finger of a wearer and having thread cutting means thereon.

Another object provides for a thimble having cutting means thereon which is expendable and may be removed and replaced.

A further object provides for means which will positively cut a thread positioned thereon.

Another object provides for a thimble having thread cutting means thereon which is protected against the accidental cutting of the user.

Other ancillary objects will be apparent from the following detailed description when read in the light of the drawings in which:

Fig. 1 is a front elevational view of the invention applied to a thimble.

Fig. 2 is a sectional view taken along line 2—2 of Fig. 1.

Fig. 3 is a sectional view taken along line 3—3 of Fig. 1.

Fig. 4 is a front elevational view of a thimble illustrating a second embodiment of the knife mounting means.

Fig. 5 is a sectional view taken along line 5—5 of Fig. 4.

Referring to the Figs. 1, 2, and 3, of the drawings, there is shown a thimble 10 having a portion thereof pressed outwardly to form a bridge 11 and apertures 12. Adjacent the upper aperture 12 is a vertical slot 13, the purpose of which will be hereinafter apparent.

A knife blade 15 having a guard 16 thereon is secured to a handle or shank 17 of relative size to the aperture 12. The handle 17 is arranged to be inserted in the apertures 12 and frictionally retained therein. The lowermost portion 20 of knife blade 15 resides within the slot 13 suffi-

ciently to position the blade below the external plane of the thimble periphery but does not extend through the said slot. Therefore, a person using the above thimble will not be cut by the portion 20 of blade 15.

As shown in Fig. 2, the blade is tapered thus insuring the cutting of the thread. The guard 16 has at the end thereof a hook member 21 which is spaced to provide a clearance between the side of the thimble and the said hook, in which the thread can be positioned. Subsequent pressure of the knife blade 15 against the thread results in the cutting thereof. In the event the pressure applied is insufficient to cut the said thread, the hook member 21 prevents the withdrawal thereof and pressure may be re-applied. The thread being pressed downwardly is eventually cut by the blade by the portion thereof adjacent the said slot.

20 A second embodiment is shown in Figs. 4, 5, wherein a bridge member 25 is secured to a conventional thimble by soldering or other means and whereby a knife 15 may be inserted in the aforementioned manner. In this embodiment the portion 20 of the blade 15 abuts against the wall of the thimble and insures cutting of thread pressed thereon.

It is readily apparent that a person utilizing the instant invention can accomplish the sewing task rapidly and efficiently without fear of accidental cutting of the material or of the fingers.

The blade assembly has been designed to be expendable, i. e., when the blade becomes dull and difficult to cut thread with, then the said assembly may be removed from the thimble and replaced with a new sharp blade assembly. The replaceable feature is desirable and is achieved by the relatively simple and inexpensive construction thereof.

40 While two forms or embodiments of the invention have been shown and described herein for illustrative purposes, and the construction and arrangement incidental to two specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

45 What I claim is:

1. The combination with a tubular member of such size as to be carried on the finger of a wearer and having an outwardly struck portion with openings above and below the portion and another opening above said openings, of thread cutting means comprising a guard provided with a shank at its lower end for insertion into the 50 openings in the struck-out portion to be sup-

ported therein, an inwardly facing hook at the upper end of the guard and two spaced walls, a removable knife positioned between said walls, a portion of the cutting edge being disposed in the upper opening.

2. The combination with a tubular member of such size as to be carried on the finger of a wearer and provided with a loop at its lower end and having an opening above the loop, of thread cutting means comprising a guard stamped from sheet metal and including a shank at its lower end which is inserted within such loop to support the guard, the central section of the guard being doubled back on itself to form two spaced walls, a knife disposed between said walls, a portion of the cutting edge thereof being disposed in the thimble opening, and an inwardly facing hook at the upper end of the guard.
